UNITED STATES PATENT OFFICE
BURIAL VAULT
John D. Renshler, Findlay, Ohio
Application July 19, 1932, Serial No. 623,415
5 Claims. (Cl. 27—35)

This invention relates to metallic vaults which are formed to provide a base and a hollow, transversely arched cover or body and particularly to a structure of this kind in which the body is hinged to the base. Vaults of this general character as ordinarily used and on the market do not have the cover hinged to the base but the cover is lifted above the base when the casket is put on the base and then the cover is lowered until the usual locks on the base and cover lock the cover to the base. Ordinarily at funerals, the base is disposed within the grave at the bottom thereof and the casket is lowered on to the base and then either the mourners wait until the cover is lowered downward through the grave and on to the base or the mourners leave and the undertaker's assistants lower this cover. The lowering of the cover into the grave in the presence of the mourners is not particularly pleasant for them as the cover is difficult to handle, is likely to scrape dirt from the sides of the grave opening which rattles down on to the casket and after the cover is in place, an undertaker's assistant must get into the grave in order to lock the cover or adjust it so that the self-locking bolts will engage. If the mourners leave the funeral ceremony before the cover is in place, they do not see the cover of the vault or that it is disposed in place over the base and casket and it leaves them with the unpleasant suggestion that no cover has been used, that the earth has been merely thrown down over the casket and at any rate, they do not see everything they have paid for.

As above remarked, practically all the vaults on the market have covers which must be lowered bodily on to the base after the casket has been put in place. Assuming that the base is raised to the level of the ground around the grave and the casket is to be put in place thereon, another difficulty arises that the pall-bearers must carry the casket into a position over the base which is supported at the level of the ground and that these pall-bearers must pass on each side of the open grave. In many cases, there is not room for the pall-bearers to do this because of the bank of earth on one side of the grave and possibly a very narrow strip of sward on the other side of the grave and in most cases the pall-bearers in carrying the casket will have to walk so close to the edge of the grave that there is great liability of the walls of the grave crumbling or breaking inward, particularly in wet weather. This causes the pall-bearers to attempt to stretch their arms out and at the same time exert suf-

ficient strength to support the casket which places great strain on the pall bearers and makes it likely that the casket may be dropped or the pall-bearers tumble. In order to avoid these very objectionable features and provide a vault which will eliminate these difficulties, my invention contemplates a vault in which the cover is hinged at one end to one end of the base so that the base may be disposed upon the usual lowering mechanism at the level of the grave mouth and the coffin may be slid endwise on to the base and into position beneath the lid, the pall-bearers carrying the casket until one end rests upon the base, the first pair of pall-bearers stepping to one side, the casket being then further shifted on the base, the second pair of pall-bearers stepping to one side, the third pair of pall-bearers sliding the casket further on to the base and then the under-taker's assistant or others shifting the casket into its proper position.

A further object of the invention is to provide means whereby the cover of the vault may be held raised until the casket is in place and then the cover gradually lowered without the necessity of the undertaker or his assistants exerting strength to prevent the falling of the relatively heavy cover upon the base and in this connection to provide hinged braces having frictional means for resisting turning movement of the braces at the point of pivotal connection so that the cover may be easily and gently lowered into place without any fall or jar, it being, of course, understood that suitable locking devices are provided for locking the vault cover to the vault base when the vault cover is fully lowered.

A further object is to provide hinges for connecting one end of the cover to one end of the base, which hinges practically form an integral part of the vault cover and base by being welded thereto, the hinges having such form as to permit the welding operation to be performed with a minimum of trouble.

Other objects will appear in the course of the following description.

My invention is illustrated in the accompanying drawing, wherein:—

Figure 1 is a perspective view of a metallic vault with the cover raised, the casket being shown in dotted lines;

Figure 2 is a fragmentary vertical sectional view through the hinged ends of the vault cover and base or pan;

Figure 3 is a fragmentary perspective view of the hinged connection between the base and vault cover;

Figure 4 is a fragmentary side elevation of the braces at the joint thereof;

Figure 5 is a section on the line 5—5 of Figure 4.

Referring to the drawing, 10 designates the usual base or "pan" which is formed with a rectangular upwardly extending hollow portion 11 and an outwardly extending flange 12. This base is formed with longitudinally extending tracks 13 or ribs upon which the casket slides, though it is to be understood that the base might be provided with any other means for supporting the casket and permitting it to slide readily into place. The vault cover 14 may have any usual or suitable shape. This vault cover is provided with opposite end walls and opposite side walls, the lower margins of the side and end walls being angularly extended downward and outward as at 15. The lower edge of this skirt 15 rests upon the flange 12 as shown in Figure 2 when the vault cover is closed. The cover may be provided with the usual handles 16 but it is to be understood that the particular construction or design of the cover has nothing to do with the present invention.

The cover 14 is hinged to the base 10 as shown in Figure 2. This hinge, it is reiterated, is disposed at one end of the base and at one end of the vault. As illustrated, the hinge consists of a plurality of hinge element 16 in the form of flat plates, each having a bead 17 at its lower end and a series of hinge elements 18, each angularly bent so as to provide an upstanding end portion 19 and at its opposite end being formed with the bead 20.

As illustrated in Figure 2, the hinge plates 16 extend upwardly against the inner face of the downwardly flaring skirt 15. The hinge elements 18 extend along the upper face of the flange 12 with the portions 19 extending upward against the vertical wall of the raised central portion 11.

The plate 16 and the plates 18 are preferably welded in place. This is readily accomplished by first welding the plate 16 to the skirt 15, then placing the vault cover on the base with the elements 18 disposed upon the skirt and the portions 19 thereof disposed against the wall of the part 11 and then spot-welding these parts 18 and 19 to the flange 12 and the upwardly extending central portion, the welder working from the outside 50 of the base. A hinge of this character practically makes the vault cover integral with the base and the hinges integral both with the base and vault. Of course, a pintle 21 extends through all of the beads 17 and 20 in an obvious manner. It will be seen that the hinge is entirely housed between the skirt and the upstanding portion 11 and it is thus protected and that the hinge cannot be cut off from the exterior of the vault. The skirt 15 fits down tightly against the flange 12 but will permit a movement of the vault cover from its closed position to a position where the vault cover is sufficiently raised to permit the insertion of the casket.

For the purpose of holding the vault cover in this raised position until it is desired to lower it, I have provided braces on each side of the vault cover, each brace consisting of two brace members 22 and 23. The brace members 23 are pivoted to the base in an obvious manner while the members 22 are pivoted to the cover.

The braces break rearward and the brace elements are pivoted to each other by a pivot bolt 24 having the wing nut 25. The adjacent ends of the brace elements 22 and 23 are relatively 75 wide-faced and by tightening up upon the nut 25

any desired frictional engagement may be secured between the contacting faces of these brace elements. Preferably, the brace element 22 is arcuately slotted as at 26 and a rivet or other stop 27 extends from the element 22 through this slot. This prevents the forward movement of the connected ends of the brace elements but permits the brace elements to be folded rearward until the vault is lowered.

While I have illustrated the brace elements 23 as exteriorly pivoted at 28, to the base, I do not wish to be limited to this. By providing this frictional engagement between the brace elements, the vault cover may be supported in its raised position until the casket has been inserted, then a slight downward pressure on the free end of the vault cover will cause the braces to fold upon each other and the frictional engagement between these braces is such that the vault cover will be almost fully supported while the cover is being lowered, thus permitting the cover to be lowered gently and noiselessly.

The vault cover is locked in place preferably by locking means such as that disclosed in Patent No. 1,862,064, granted on the 7th day of June, 1932.

It will be seen that with this construction the pall-bearers do not have to walk on each side of the grave with the liability of causing the grave to cave in and with the difficulties attendant to attempting to support the heavy casket under these circumstances. Ordinarily with the usual vault covers, they are laid to one side on the grass and sometimes in the dirt made by digging the grave.

These vault covers must be then lifted by the undertaker's assistants and carried over to and placed upon the base or lowered down on to the base if the base be lowered into the bottom of the grave and this is difficult and requires services of several assistants, requires great care in order to get the cover properly disposed upon the base, the grass beside the grave is trampled and there is liability, as there is in the case of pall-bearers, of the grave giving in under the weight of the men carrying the vault cover and putting it in place. This difficulty is entirely done away with by hinging the cover to the base as the cover and base are simply placed in position upon the usual lowering device prior to the funeral and the casket slid gently into position without any trampling of the grass around the grave and the cover then lowered into place and locked after which the base with the enclosed casket and the closed cover may be lowered into place. The hinging of the cover at one end is important not only for the reasons heretofore stated, that it permits the casket to be slid endwise on to the base making it much more readily handled by the pall-bearers but because if the cover were hinged to the side of the base and turned upward, it would be impossible for one set of pall-bearers to handle one side of the casket. The pall-bearers would have to carry the casket, under these circumstances, into a position parallel to the side of the base, then two men would have to shift the casket laterally into position on to the base which would be very difficult to do. This is entirely obviated by hinging the cover to the end of the base.

With this construction, the bereaved family sees the complete and fully finished vault at ground level. The pall-bearers merely place the end of the casket on the edge of the vault base. The casket is easily and quietly slipped into place.

and when in place, the cover is gently lowered and automatically locked. The family thus know that the burial is fully completed and know that the vault is completely locked and water and air-tight.

5 I claim:—

1. A burial vault including a metallic base and a metallic, transversely arched cover, the cover and base being elongated in one direction to provide relatively narrow end portions and relatively long side portions, the cover being hinged at one end to one end of the base, and means acting to support the cover in its raised position and frictionally resist downward movement of the cover.
- 10 2. A burial vault including a base of sheet metal having a centrally raised casket supporting portion and a base flange, a metallic cover having top, side and end walls, the end walls being narrow relative to the side walls, the lower margins of the end walls being outwardly flared, and a hinge element secured to the flange at one end of the base and to the outwardly flaring portion of the like end of the cover.
- 15 3. A burial vault comprising a base of sheet metal having a central raised casket supporting portion and an outstanding base flange and a metallic cover having top, side and end walls, the end walls being narrow relative to the side walls, one of the end walls being downwardly and out-

wardly flared, and hinge elements pivotally connected to each other, certain of the hinge elements being welded to the downwardly flaring end portion of the cover, the other hinge elements being welded to the flange at one end of the base.

5 4. A burial vault comprising a base of sheet metal having a central raised casket supporting portion and a base flange, a cover having top, side and end walls, and fitting over the base, one of the end walls being downwardly and outwardly flared, flat hinge plates welded to the inner face of the flared portion of said end wall, angular hinge plates hingedly connected to the first named set of plates and welded to the base flange of the base and against the side wall of the raised portion of said base.

10 5. A burial vault including a metallic base and a metallic, transversely arched cover, the cover being hinged at one end to one end of the base whereby the cover may be lifted up at one end to receive the casket, and braces engaging with the cover and base, the braces being formed of two sections, the sections overlapping at their junction, a bolt pivoting the sections to each other and having a nut whereby the frictional engagement between the sections may be increased or decreased, and means limiting the movement of the sections relative to each other in one direction.
